James Wager, Volney Richmond, & Harvey Smith,
of Troy, N. Y.

Letters Patent No. 613. Dated Dec. 20th, 1853.

The schedule referred to in these Letters Patent, and making part of the same:

To all whom it may concern:

Be it known that we, James Wager, Volney Richmond, and Harvey Smith of Troy in the County of Rensselaer, and State of New York, have invented or produced a new and original design of parlor stove which we call the "Iliion," and we do hereby declare that the following is a full clear and exact description of the same, reference being had to the annexed drawings making a part of this specification in which fig. 1 is a perspective view of the stove, and fig. 2 is a perspective view of the back lower plate of the same.

The description of our design of parlor stove is as follows, viz: A, fig. 1 is the front plate ornamented at the lower corners with the scrolls (aa), on the sides with the scroll mouldings (bb), and at the top with the inverted arched mouldings (cc). (dd) are sunk panels. B is the revolving blower decorated around the edge with the ornamental moulding (e). The center is ornamented with the scrolls (ff), shell (g), arched mouldings (h) and ovolos (i). C is the lower top plate, with the ornamental shell border (j). D is the upper front plate decorated with the ornaments (kk), (ll), and the mouldings (mm). E is the upper top plate, with the ornamental bordering (nn) and the scroll and shells (pp) arranged upon the surface. F is the urn, the cover of which is decorated with a scalloped border (qq) and ornament (rr). G is the upper side plate decorated with the ornament (ss). H is the lower side plate with the ornamental mouldings (tt) arranged on the top and sides. (uu) are arched recesses at the bottom of the plate. I is the fire door, with the ornament (vv) on the panel, and the decorative mouldings (ww) arranged at the top sides. J is the bottom plate, decorated at each corner with the shells (aa'), and the ornamental moulding (bb'). K is a movable hearth plate, with the register (cc'), and ornamental mouldings (dd'). L is the leg ornamented with the flats (ee') and ovolos (ff'). M, fig. 2, is the lower back plate decorated on each side with the scroll ornaments (gg'), the hortic mouldings and arches (hh') arranged in the center. (jj') are a series of arched ribs or projections arranged on the bottom edge of the plate.

Having thus described our new design of parlor stove, what we claim as new and desire to secure by Letters Patent, is the ornamental design & configuration of parlor stove plates, such as herein described, and represented in the annexed drawings.
